UNITED STATES PATENT OFFICE

2,435,163

MEANS FOR FORMING SEWING RIBS FOR
WELT-TYPE INSOLESVictor A. Sherbrook, East Millbury, Mass., as-
signor to Paul O. MacBride, Waban, Mass.

Application May 27, 1946, Serial No. 672,351

14 Claims. (Cl. 12—27)

1

This invention relates to means for removing a strip from the "feather" of a welt-type insole having a preformed sewing rib, for the purpose of reducing the thickness of the feather so that the same may be folded up into close association with the sewing rib to be secured thereto for strengthening the same and also to do away with the feather itself.

It has been recognized in the art that it is a desirable feature to avoid the use of a feather in a welt-type insole and it has been proposed as shown in Patent No. 2,379,480, July 3, 1945, to make the sewing rib as customary but to add to the rib a further strip which comprises the "feather" after the latter has been considerably reduced in thickness by removing a strip therefrom at the flesh side of the leather. When this strip has been removed, the remaining grain side of the feather is easily folded upwardly into contact with the sewing rib to strengthen the same and to do away with the feather completely. Advantages of this construction are enumerated in the patent above referred to.

This invention has for its primary object provision of means for easily and quickly reducing the feather by removing a strip therefrom at the flesh side thereof and comprising a slitting knife which is adapted to travel relative to the insole to slit the strip above referred to in combination with a constant pressure guide impinging the sewing rib at the opposite side thereof, i. e., the interior aspect of the sewing rib with respect to the insole, and a presser gauge located directly in front of the blade in close relation thereto to aid in guiding the blade and to insure proper thickness of cutting thereof; the cutting blade, the pressure guide, and the presser gauge all being generally fixed together in a single unit and having a reciprocatory motion in the direction of the length of the feather of the insole to accomplish the purpose described; further in combination with a holding foot which is serrated to contact the feather in advance of the cutter and presser gauge for the purpose of either of feeding the insole or of holding the same during the cutting stroke of the blade, said holding foot having a vertically reciprocatory motion at right angles to the direction of reciprocatory motion of the unit aforesaid, to the end that the strip removed from the feather shall be uniform in depth and width and easily cut and removed even around the sharp arc at the toe of the insole.

Further objects include the provision of a device as above described wherein the presser gauge

2

is recessed or hollowed out to receive the holding foot therein so that the latter may approach relatively to the cutting blade as closely as possible for greater accuracy during the cutting operation, it being understood that the presser gauge is interposed between the cutting blade and the holding foot, and it is particularly pointed out that the provision of the holding foot to impinge the feather is an important part of this invention because of the improved result in the cutting action over prior art devices wherein a holding foot is used to impinge on the insole within the sewing rib and not on the feather.

Other objects and advantages of the invention will appear hereinafter.

Reference is to be had to the accompanying drawings, in which

Fig. 1 is a perspective view illustrating the invention,

Fig. 2 is a view similar to Fig. 1 but showing the parts separated for clarity of illustration,

Fig. 3 is a view in front elevation, parts being in section,

Fig. 4 is a view in end elevation, the insole being in section, and

Fig. 5 is a view showing a modified holding foot.

In Fig. 1 the insole is indicated at 10 and this insole has already been guttered at 12 to form a part of the sewing rib 14 which extends upwardly from the insole. The feather is shown at 16. As clearly shown in Figs. 1, 2, and 3, the present device is provided for the purpose of reducing the thickness of the feather 16 by slitting or cutting off a strip 18 from the flesh side of the insole leaving a thin grain side 20 to be folded up into contact with the sewing rib 14 for the purpose described.

A knife holder is indicated generally at 22 and this holder may be of conventional design and is adapted to hold a blade 24 therein. As is well known in the prior art, the blade holder is secured as by a fastener in slot 26 to a vibratory arm which is power driven so as to provide a reciprocatory motion to the blade holder and blade in the direction of the arrow 28 in Fig. 3, that is, parallel to the feather.

This invention provides a constant pressure guide to impinge and run on the sewing rib 14 as most clearly shown in Fig. 4. This pressure guide comprises a lever having a portion 30 riding against the rib 14 directly opposite the knife blade 24. The other end of the lever comprises a handle 32 which is spring pressed in a counter-clockwise direction in Fig. 4 by means of a spring

34 which finds a bearing point on a bracket 36, the latter being vertically adjustable by means of a screw 38 in a bracket 40. Bracket 40 and knife blade holder 22 are secured to the same power driven element for simultaneous motion.

A presser gauge 42 is also secured to the same power driven element and this gauge rides on the feather 16 in closely spaced relation to the cutting edge of the knife blade, gauging the depth of the cutting thereof and closely holding the feather so as to provide a positive, smooth acting cut by the blade 24. The actual relation of these parts is clearly shown in Fig. 1 and is shown spaced in Fig. 2 for a better understanding of the relationship thereof.

The presser gauge is hollowed out or recessed at the side opposite the sewing rib as clearly shown at 44 for the purpose of receiving partially therein a holding foot 46, the latter being serrated on the bottom for the gripping of the feather. This construction provides a substantial width for the presser gauge along the rib 14 and at the same time allows the holding foot 46 to come as close as possible to the cutting edge of the blade 24. The holding foot is secured to a bracket 48 to which is imparted a vertical reciprocatory motion as shown by arrows 50 in Fig. 3.

In the operation of the device the unit comprising the three members, blade 24, constant pressure guide 30, and presser gauge 42, is rapidly reciprocated as described so as to cut the strip 18 as shown by short, rapid steps and it will be seen that this strip will always be uniform due to the guide and the gauge described, this uniformity extending both to width of cut and depth of cut as will be readily understood. The holding foot may be used to hold the insole just during the cutting steps and due to the recess 44 this holding foot will come as close as is possible to the leading edge of the knife blade. The operation is that the cutting knife moves to the left in Fig. 3 when the holding foot 46 is down and then moves to the right in Fig. 3, whereupon the holding foot rises and tends to allow forward feed of the insole either by hand or by the action of the knife blade in holding the cut strip 18. Of course, it will be seen that the holding foot 46 may be reciprocated in the same direction as the cutting unit to actually push the insole along, and this also comes within the scope of the present invention.

This invention also contemplates a holding foot 46' provided with a second part 48' contacting the insole inside of the rib 14, so that the rib is straddled thereby and the insole is impinged at both sides of the rib.

Having thus described my invention and the advantages thereof, I do not wish to be limited to details herein disclosed otherwise than as set forth in the claims, but what I claim is:

1. The combination with a slitting knife and a constant pressure rib guide of a relatively movable holding foot engaging the feather of a welt-type insole, said knife slitting the feather longitudinally to remove a part thereof, said knife and guide having a reciprocatory motion in the direction of cut and the holding foot having a reciprocatory motion transverse to the feather, the knife cutting in one direction of its movement, and the holding foot engaging and holding the uncut feather during the cutting action.

2. The combination of claim 1 including a second foot on the holding foot spaced therefrom and engaging the insole at the opposite side of a

sewing rib on the insole, so that the two holding feet straddle the rib.

3. Apparatus for removing a strip from the feather of an insole having a sewing rib comprising a knife arranged to relatively travel along the feather and slit the same, a pressure guide engaging the rib at the side opposite from the feather at a point adjacent the knife, the knife and the guide traveling together as respects the 10 said feather, and a holding foot engaging the uncut feather just in front of the knife.

4. Apparatus for removing a strip from the feather of a welt-type insole having a preformed sewing rib, to reduce the thickness of the feather, 15 comprising a knife, a pressure guide engaging the rib in the region of the knife at the side of the rib opposite the knife, a pressure gauge associated with the knife in substantially fixed operative relation thereto and bearing on the feather just in advance of the cutting edge of the knife, 20 said guide, gauge, and knife having a motion relative to the feather to cut the latter, and means holding the feather in advance of the knife.

5. Apparatus of claim 4 wherein said means 25 comprises a holding foot reciprocable transversely to the feather at the opposite side of the gauge from the knife.

6. Apparatus of claim 4 wherein said means comprises a feather-engaging holding foot reciprocable vertically to and from the feather, the 30 knife, guide and gauge being reciprocable together as a unit in the direction of the length of the feather.

7. Apparatus of claim 4 wherein said means 35 comprises a feather-engaging holding foot reciprocable normally to the feather, the knife, guide, and gauge being relatively reciprocable in the direction of the length of the feather, and a recess in the gauge receiving the holding foot to 40 approach the latter closer to the knife at intervals when the holding foot and gauge come into closest contact during the cutting action.

8. Apparatus for trimming the feather of a welt-type insole having a sewing rib comprising a knife, a pressure guide engaging the rib at the interior side thereof, the knife being located to 45 cut the feather, a presser gauge for the knife engaging the feather in advance of the cutting edge of the knife, the gauge and knife being in relatively fixed relation, a recess in the gauge at the side of the latter opposite the knife, a feather-holding foot intermittently operable to hold the feather during cutting, said foot being partially received in said recess to bring the foot as close as 50 possible to the knife edge.

9. Apparatus for trimming the feather of a welt-type insole having a sewing rib comprising a knife, a support, a pressure guide for the knife thereon, said guide engaging the rib at the opposite side thereof from the knife to guide the latter relative to the rib, and a feather-holding foot engageable with the feather in advance of the knife. 55

10. Apparatus of claim 9 wherein said pressure 60 guide comprises a lever movable relative to the support and resilient means constantly urging an end of the lever toward the rib.

11. Apparatus of claim 9 wherein said pressure 65 guide comprises a lever pivoted to the support and including a spring to urge one end of the lever into engagement with the rib, the other end of the lever acting as a handle.

12. Apparatus for reducing the thickness of the feather of a welt-type insole having a rib comprising a unit capable of reciprocation in the direction of the length of the feather, said unit 70

comprising a knife in position to cut the feather, a presser gauge engaging the feather adjacent and in advance of the knife edge and a pressure guide engaging the rib at the side thereof opposite the knife, and a feather-holding foot reciprocable normal to the feather and transverse to the direction of reciprocation of the unit in position to substantially engage the presser gauge during the cutting stroke of the unit.

13. Apparatus of claim 12 wherein the presser gauge is provided with a recess in position to at least partially receive the feather-holding foot.

14. Apparatus of claim 12 wherein the presser gauge is provided with a recess at the side thereof facing the holding foot, said holding foot extending partially into said recess during cutting action of the knife.

VICTOR A. SHERBROOK.
